UNITED STATES PATENT OFFICE.

VICTOR H. SLINACK, OF PHILADELPHIA, PENNSYLVANIA, ASSIGNOR TO PENNSYLVANIA GLOBE GAS LIGHT COMPANY, OF PHILADELPHIA, PENNSYLVANIA, A CORPORATION OF PENNSYLVANIA.

INVERTED INCANDESCENT GAS-LIGHT.

1,089,504.

Specification of Letters Patent. Patented Mar. 10, 1914.

Application filed June 29, 1911. Serial No. 635,976.

To all whom it may concern:

Be it known that I, VICTOR H. SLINACK, a citizen of the United States, and a resident of Philadelphia, in the county of Philadelphia and State of Pennsylvania, have invented a certain new and useful Inverted Incandescent Gas-Light, of which the following is a specification.

The principal object of the present invention is to provide a comparatively simple, durable and reliable hanging lamp for lighting inverted mantles by means of gas under considerable pressure and which shall in operation produce an extremely brilliant and steady light without becoming unduly heated.

Other objects will appear from the following description taken in connection with the accompanying drawings forming part hereof, and in which—

Figure 1, is a side view principally in central section, illustrating a light embodying features of the invention and provided with one burner. Fig. 2, is a similar view illustrating a modification of the invention and showing a light provided with two burners, and Fig. 3, is a sectional view illustrating a detail of construction embodying a modification of the invention.

In the drawings 1 is a casing having the usual reflector *a*, and provided at its top with a ventilator 2 and having a double side wall 3—4, and a bottom wall 6 connecting the said side walls and provided with air inlets 5 to constitute an air supply chamber which is of generally annular form and surrounds the body of the lamp.

7, is a globe arranged beneath the outer wall 4, with air inlet space 8 above it and below the bottom wall 6.

9, is a deflector or baffle plate having a burner opening and an encircling hood 10, and both the deflector and hood are arranged beneath the inner wall 3 with space 11 between them.

12, is a gas pipe which carries a yoke 13 having arms which support the casing and also brackets 14 that carry the wall 6, the hood 10 and the brackets 15 from which the deflector 9 is suspended.

Referring more particularly to Fig. 1, 16 is a fitting carried by the gas pipe and provided with an air mixing tube 17, having an

inverted mantle 18 depending through the burner opening in the deflector and said fitting is also provided with a jet orifice 19, which may be removable, and discharges into said tube and with an air intake chamber 20 communicating with the space between the double walls of the casing and in closing the jet orifice and mixing tube.

21, is a shutter which may be turned from the outside of the casing and which serves to admit more or less air from the space between the double walls of the casing to the interior of the chamber 20 and to the mixing tube 17. The shutter may be removed and access had to the section 22 that carries the jet orifice, so that it can be unscrewed and removed so as to be cleaned.

23 are dirt catchers arranged in the fitting and they serve to insure a clean supply of gas to the jet orifice 19.

The arrangement shown in Fig. 2, is substantially the same as has been described, except that a double fitting 16^a is employed instead of a single one and it contains the gas cleaner or dirt catcher 23^a, which can be removed for cleaning without disturbing the other parts.

The arrangement shown in Fig. 3, is substantially the same as has been described more particularly in connection with Fig. 1. However in Fig. 3, the fitting 16^b, is straight and not provided with elbows so that gas 85 from pipe 12, passes through the cleaner 23^b, and thence to jet 19 which is shown as formed in a plug screwed into the fitting.

In the constructions of Figs. 1, 2, and 3, the fitting is carried from the end of the gas pipe.

24, is a deflector arranged above the fitting and carried by the gas pipe.

25, is a pilot light tube which is provided at its lower end near the mantles with a 95 perforated screen 26, which protects the small pilot light flame from being extinguished by draft.

27, is a globe ring hinged at 28 and provided with a latch 29 coöoperating with a keeper 30. This latch is capable of manipulation by one hand and by reason of the construction of the latch and its keeper this can be done even when the globe is hot.

Pure air uncontaminated by products of 105 combustion enters at 8 and impinges upon

2

and is divided by the hood 10, which also protects the mantles and burners from direct drafts. Part of the air rises through the openings 5 and reaches the annular in-
 5 closure around the casing and from this inclosure air is admitted in desired or prop-
 erly regulated quantity past the shutter 21, to the chamber 20, and thence to the air and
 gas mixing tube 17. Part of the air circu-
 10 lates into the globe and keeps it cool and ris-
 ing, supplies the mantles, and with the prod-
 ucts of combustion escapes at the ventilator.
 The described circulation of air continues
 15 as long as the lamp or light is burning and
 thus properly supports combustion and keeps
 the parts from being over-heated.

The part 16, hereinabove called a fitting,
 is an element through which gas passes and
 which is provided with a lateral hole in
 20 which the section 22, is detachably mounted
 as by a screw thread connection. The sec-
 tion 22, is provided with the gas orifice 19.
 By removing part 21, the section 22, can be
 25 withdrawn through the side wall of the
 lamp casing without disturbing the other
 parts of the lamp.

What I claim is:

1. An inverted incandescent gas light com-
 30 prising the combination of a casing provid-
 ed with a ventilator and having a double
 wall constituting an air supply chamber, a
 globe beneath the outer part of the double
 wall with air inlet between it and the bot-
 35 tom of said outer part of the double wall, a
 deflector having a burner opening and hav-
 ing a hood encircling the deflector with space
 between and both arranged beneath the
 inner part of the double wall, a gas pipe,
 40 and a fitting carried by the gas pipe and
 provided with an air and gas mixing tube

having an inverted mantle depending
 through the burner opening, and provided
 with a jet orifice discharging into said tube
 and provided with an air intake chamber
 45 communicating with the air supply cham-
 ber and inclosing the jet orifice and mixing
 tube and forming an annular air chamber
 co-extensive with the mixing tube, substan-
 tially as described.

2. An inverted incandescent gas light com-
 50 prising the combination of a casing provided
 with a ventilator and having a double side
 wall and a perforated bottom wall connecting
 the side walls and constituting an air sup-
 55 ply chamber, a globe beneath the outer wall
 with air inlets between it and the bottom wall
 of the casing, a baffle plate arranged at the
 center of the casing, having a burner open-
 60 ing and a hood encircling the baffle plate
 with space between for the passage of prod-
 ucts of combustion and air and both ar-
 ranged beneath the inner wall, a gas pipe,
 65 and a fitting carried by the gas pipe and
 provided with an air and gas mixing tube
 having an inverted mantle depending
 through the burner opening, and provided
 with a jet orifice discharging into said tube
 and provided with an air intake chamber
 70 communicating with the space between the
 double wall and inclosing the jet orifice and
 mixing tube forming an annular air cham-
 ber concentric and co-extensive with the
 mixing tube, substantially as described.

In testimony whereof I have hereunto
 signed my name.

VICTOR H. SLINAOK.
